UNITED STATES PATENT OFFICE

109,705

DESIGN FOR A SERVICE STATION BUILDING OR THE LIKE

Herbert L. Ebling, Milwaukee, and Henry P. Plunkett, Shorewood, Wis.

Application December 24, 1937, Serial No. 73,847

Term of patent 3½ years

To all whom it may concern:

Be it known that we, Herbert L. Ebling and Henry P. Plunkett, citizens of the United States, residing, respectively, at Milwaukee and Shorewood, in the county of Milwaukee and State of Wisconsin, have invented a new, original, and ornamental Design for Service Station Buildings or the like, of which the following is a specification, reference being had to the accompanying drawing, forming part thereof.

Figure 1 is an elevational view of one side of a service station building or the like, showing our new design.

Figure 2 is an elevational view of the other side of a service station building or the like, showing our new design.

Figure 3 is a view of one end thereof.

Figure 4 is a view of the other end thereof.

Figure 5 is a top plan view of the design.

We claim:

The ornamental design for a service station building, or the like, substantially as shown.

HERBERT L. EBLING.
HENRY P. PLUNKETT.
